CLAIM

The ornamental design for an external vehicle side storage compartment assembly as shown and described.

DESCRIPTION

FIG. 1 shows an isometric view of a left-side external vehicle side storage compartment assembly according to a first embodiment, shown positioned between a rear tire and a rear bumper on the left side of a vehicle.

FIG. 2 is a front elevation view of a left-side external vehicle side storage compartment assembly according to a first embodiment.

FIG. 3 is a top elevation view of a left-side external vehicle side storage compartment assembly according to a first embodiment.

FIG. 4 is a rear elevation view of a left-side external vehicle side storage compartment assembly according to a first embodiment.

FIG. 5 is a bottom elevation view of a left-side external vehicle side storage compartment assembly according to a first embodiment.

FIG. 6 is a right elevation view of a left-side external vehicle side storage compartment assembly according to a first embodiment.

FIG. 7 is a left elevation view of a left-side external vehicle side storage compartment assembly according to a first embodiment.

FIG. 8 shows an isometric view of a right-side external vehicle side storage compartment assembly according to a second embodiment, shown positioned between a rear tire and a rear bumper of a vehicle.

FIG. 9 is a front elevation view of a right-side external vehicle side storage compartment assembly according to a second embodiment.

FIG. 10 a top elevation view of a right-side external vehicle side storage compartment assembly according to a second embodiment.

FIG. 11 is a bottom elevation view of a right-side external vehicle side storage compartment assembly according to a second embodiment.

FIG. 12 is a side elevation view of a right-side external vehicle side storage compartment assembly according to a second embodiment.

FIG. 13 is a bottom elevation view of a right-side external vehicle side storage compartment assembly according to a second embodiment; and,

(Continued)

FIG. 14 is a side elevation view of a right-side external vehicle side storage compartment assembly according to a second embodiment.

Broken lines denote unclaimed subject matter illustrating the environment of the claimed design and form no part of the claimed design.
